(No Model.)

UNITED STATES PATENT OFFICE.

DAVID B. ALLEN AND EDWARD K. WARREN, OF THREE OAKS, MICHIGAN.

WHIP.

SPECIFICATION forming part of Letters Patent No. 375,974, dated January 3, 1888.

Application filed July 12, 1887. Serial No. 244,081. (No model.)

To all whom it may concern:

Be it known that we, DAVID B. ALLEN and EDWARD K. WARREN, both of Three Oaks, in the county of Berrien and State of Michigan, 5 have invented a new and useful Improvement in Whips, of which the following is a full, clear, and exact description.

This invention relates to whips which have their bodies or stocks made up of different materials possessing different degrees of strength and elasticity, and in which the strongest or more elastic material is placed as near the exterior surface of the whip as convenient, for the purpose of more effectually resisting the 15 strain when using or bending the whip, which strain is much more severe upon the surface than toward the center of the whip. An efficient description of whip having this object in view, and which also provides for using a solid 20 center or core proper of inferior material and still produces a very serviceable whip, is shown and described in an application for patent for a whip-core, Serial No. 228,208, by E. K. Warren, filed February 19, 1887, and our invention 25 in a measure resembles it.

In the whip-core of Warren, however, here referred to, the whip-center was formed of a core having longitudinal grooves in its exterior surface, and cords, which constitute the superior or stronger material, inserted within said grooves to add to the strength of the core, the whip being afterward finished in the usual or any suitable manner—as, for instance, by stocking it with the usual side pieces and subsequently putting the whole into a lathe and turning it round and tapering it, and then inclosing it by a plaited cover and coating of suitable material or otherwise.

Our invention accomplishes like ends in a 40 different manner or by a different construction. Thus we cut or groove the stocking or side pieces of the whip on their under or inner sides, and insert or lay within said cut surfaces or grooves the stiffening cords or blades outside of the center piece or core proper, and so bring the superior or stronger material very close to the exterior surface of the whip.

Reference is to be had to the accompanying drawings, forming a part of this specification, 45 in which similar letters of reference indicate corresponding parts in all the figures.

Figure 1 represents a short length of one of the siding-pieces of a whip, as seen from its under or inner side, and showing the groove, which may be of any desired size and shape, 55 ready to receive the stiffening cord or blade within it. Fig. 2 is a like view of the same, with the piece or pieces of stiffening material secured within the longitudinal groove of the siding-piece. Fig. 3 is a longitudinal exterior 60 view showing the grooved siding-pieces having the stiffening cords or blades within them when or after the whole are placed about the central core, and Fig. 4 shows a partly-broken finished longitudinal portion of the whip. Figs. 65 5, 6, and 7 are transverse sections of the parts and constructions illustrated in Figs. 1, 2, and 3.

A indicates the central core or inner body part, which may be made of any suitable material, including whalebone and rattan.

B B are the siding-strips, which are placed and glued or secured as usual, or in any suitable manner, about or around the core A, as whip-cores have before been stocked, for instance. These siding-strips B B, which may be made of rattan or any other suitable material, have longitudinal recesses, cuts, or grooves b, of any desired size and shape, made in their under or inner sides, into which are inserted, 80 as by gluing and tying, or otherwise, cords or blades C, of feather-bone, whalebone, horn, steel, rubber, leather, wire, or textile or other suitable stiffening material adapted to give strength or elasticity to the whip. These stiffening cords or blades C, of which there may be any number in each groove or recess b, we insert in the siding-strips B before building up the latter around the central core, A, after which the whole is turned on the exterior, as 90 usual, and so that a large or greater portion of the siding is turned away, as shown in Fig. 7, leaving the stiffening cords or blades C near the outer surface of the whip. The entire whip may then be finished on the exterior with a 95 covering, e, as usual, or otherwise.

The construction of the whip, as described, provides for placing the strengthening or elastic filling cords or blades of the whip almost at the extreme surface thereof, where the best possible results may be secured, and, if desired, an inferior core or center may be used.

Having thus described our invention, what we claim as new, and desire to secure by Letters Patent, is—

1. The separate siding strips or pieces of the whip, having longitudinal grooves or recesses in their inner surfaces, in combination with a series of independent stiffening cords or blades separately inserted and secured within each of said grooved or recessed portions of the siding-strips, essentially as described.
2. In a whip, the combination of the cen-

tral core, A, the siding strips or pieces B, built around said core, and having longitudinal grooves or recesses in their inner surfaces, and stiffening cords or blades C, inserted with in said grooved siding-strips outside of the central core, substantially as specified.
